US00D719747S

(12) **United States Design Patent**
Mischel, Jr. et al.

(10) **Patent No.:** **US D719,747 S**
(45) **Date of Patent:** ** *Dec. 23, 2014

(54) **LIGHTED MIRROR**

(75) Inventors: **James Vernon Mischel, Jr.**, Seattle, WA (US); **Patrick Daniel Erickson**, Seattle, WA (US); **Sheryl Danielle Ray**, Seattle, WA (US)

(73) Assignee: **Electric Mirror, LLC**, Everett, WA (US)

(*) Notice: This patent is subject to a terminal disclaimer.

(**) Term: **14 Years**

(21) Appl. No.: **29/258,446**

(22) Filed: **Apr. 22, 2006**

(51) **LOC (10) Cl.** **06-07**

(52) **U.S. Cl.** USPC **D6/309**

(58) **Field of Classification Search**
